Primary Examiner — Wan Laymon(74) *Attorney, Agent, or Firm* — Andrew F. Young, Esq.;
Lackenbach Siegel, LLP(57) **CLAIM**The ornamental design for a key wedge, as shown and
described.**DESCRIPTION**

This application relates to PCT/US2015/021266 filed Mar. 18, 2015 which in turn relates to U.S. Prov. Ser. No. 61/955,274 filed Mar. 19, 2014 the entire contents of each of which are incorporated herein by reference.

FIG. 1 is a front perspective view of the key wedge.

FIG. 2 is a top plan view of FIG. 1.

FIG. 3 is a bottom plan view of FIG. 1.

FIG. 4 is a rear elevation view of FIG. 1.

FIG. 5 is a front side elevation view of FIG. 1.

FIG. 6 is a left side elevation view of FIG. 1; and,

FIG. 7 is a right side elevation view of FIG. 1.

The present invention is a key wedge for use in a medical device.

The broken lines and dashed-dot-dot lines shown in the figures represent portions of the key wedge that form no part of the claimed design. The surfaces are lightly lined for contour only.
